WASTE GRAB PREVENTER

Walter M. Gibbs, Chicago, Ill.

Application February 3, 1939, Serial No. 254,394

3 Claims. (Cl. 308—89)

My invention contemplates and provides novel, simple, and effective means for preventing waste grabs and thus avoiding consequent hot boxes.

In the parlance of railroading a "waste grab" occurs when a rotating journal, operating in a journal box supported thereby, carries threads or chunks of lubricating packing upwardly to the bearing brass (or other journal-engaging box-supporting shoe) for lodgment between the brass and journal, such lodgment being permitted by momentary separations of brass and journal resulting from the jolts and jars of traffic. When so lodged, the "grabbed" packing material, acting very much like a squeegee, prevents the very necessary continuous film of oil from existing between the brass and journal. The results, of a waste grab, unless it is speedily discovered, and corrected, are a hot box and sometimes a destroyed journal—possibly a wreck.

Waste grabs occur most frequently in cold weather when the oil which saturates the packing is quite stiff. However, waste grabs occur at all times of the year. The "grabbed" packing material usually comes from the upper surface of the packing contained in the journal box, but it does, in some cases, come from below the upper surface of the packing.

The term "bearing brass" as hereinafter used in this specification, should be regarded as broad enough to include any box-supporting journal-engaging shoe of whatsoever material or materials made.

In its most simple and preferred form, the waste grab preventer of the present invention consists of a metal sheet (preferably but not necessarily of brass) which is conformed to constitute a partial sleeve which snugly embraces, and by its inherent springiness clings to, the major portion of the cylindrical surface of a journal (at rest or in rotation) which is not in the embrace of the bearing brass. The longitudinal edges of the partial sleeve are preferably provided with flanges adapted to engage the bearing brass to insure that such partial sleeve cannot have either of its longitudinal edges become caught between the journal and the bearing brass. That portion of the partial sleeve which lies beneath the upper surface of the packing is provided with a plurality of apertures through which the packing may contact the cylindrical surface of the journal and effect its lubrication. The portions of the partial sleeve which lie above the upper surface of the packing are imperforate, or substantially imperforate—preferably entirely

imperforate for some distance above the packing both fore and aft of the journal.

In a modified embodiment of my invention the longitudinal edges of the waste grab preventer are conformed to interengage with portions of the bearing brass to prevent the waste grab preventer from moving longitudinally of the journal into engagement with either the collar (end flange) or fillet (shoulder) of the journal. Such modified embodiment of my invention is also characterized by a plurality of oil collecting grooves which are formed on the inner surface of that portion of the waste grab preventer which is apertured to allow contact of the packing with the journal.

These and other objects, features and advantages of my invention will appear from the following detailed description, wherein reference is made to the accompanying three sheets of drawings, in which

Fig. 1 is a vertical section, through a conventional journal box assembly, which is taken in a plane parallel with the journal axis—the journal being shown in elevation and the waste grab preventer partially in elevation and partially in section;

Fig. 2 is a section, transverse to the journal axis, taken in the plane of the line 2—2 of Fig. 1 and looking in the direction indicated by the arrows;

Fig. 3 is a fragmentary sectional view, taken in the same plane as Fig. 2, but on larger scale, illustrating portions of the journal, bearing brass, packing and waste grab preventer;

Fig. 4 is an isolated perspective view of the waste grab preventer of the preceding figures;

Fig. 5 is a view generally corresponding to Fig. 1 but illustrating a modified form of the waste grab preventer;

Fig. 6 is an isolated perspective view of the waste grab preventer of Figs. 5, 7, and 8;

Fig. 7 is a horizontal sectional view which may be regarded as taken in the several horizontal planes of the line 7—7 of Fig. 5, a portion of the brass bearing being shown in top plan and the remainder being broken away to reveal parts therebeneath; and

Fig. 8 is a view corresponding generally to that of Fig. 3, but illustrating the modified form of waste grab preventer in its appropriate relationship to the elements with which it cooperates.

Similar characters of reference refer to similar parts throughout the several views.

In the accompanying drawings reference numeral 10 denotes what is or may be a conven-

tional box for the journal 11 of an axle 12. The journal box 10, as illustrated, comprises the usual opening 13 normally closed by cover 14, and the usual dust guard well 15 in which is disposed a 5 suitable dust guard represented as a whole by reference numeral 16. At 17 is depicted the usual bearing brass which, in the present instance, is provided with babbitt lining 18. The usual or any suitable bearing brass wedge is indicated at 19. 10 The journal 11, being of conventional design, comprises the collar or end flange 20, and the shoulder or fillet 21.

Disposed in the lower portion or well of the journal box 10 is a suitable quantity of oil soaked 15 packing 22, which usually consists of wool waste or cotton waste having coiled springs interspersed therewith. The packing depicted in the accompanying drawings may be presumed to have been placed in accordance with approved present-day 20 railway practice, and may be regarded as consisting of three portions, namely the back roll 22-a, the principal packing body 22-b and the front plug 22-c. The upper surfaces of those packing portions (back plug 22-a and principal 25 packing body 22-b) which lie under and partially around the cylindrical surface of journal 11 are at a level somewhat below the horizontal plane which includes the journal axis. In fact, the horizontal plane of the upper surfaces of 30 such portions of the packing is usually approximately one inch below the horizontal plane which includes the axis of the conventional journal found in general use by American railroads.

The several elements thus far mentioned in 35 this detailed description of the accompanying drawings, are old. They have been shown and described because collectively they constitute a preferred environment for the now-to-be-described waste grab preventer which is the salient 40 feature of the present invention.

The waste grab preventer, in its more simple form of Figs. 1 to 4 inclusive, consists of a sheet 45 of metal, preferably but not necessarily brass, which is conformed to constitute a partial sleeve 11 which will snugly embrace the greater portion of so much of the cylindrical surface of journal 11 as is not embraced by the concavity of bearing brass 17 (see Fig. 2). Such partial sleeve 50 possesses inherent resiliency in the sense that when it is removed from the journal its longitudinal (upper) edges assume positions wherein they are closer together than are the closest positions which they are permitted to assume when such partial sleeve is embracing the journal. 55 Consequently, the waste grab preventer, by virtue of such inherent resiliency, acts to hold itself snugly upon the portion of the journal which it embraces, and maintains that position, despite relative rotation of the journal in either direction.

The longitudinal edges of the waste grab preventer are provided with outwardly turned flanges 24. Such waste grab preventer also has imperforate lateral portions 25-25 and a perforate 60 intermediate portion 26. The apertures in the perforate portion 26 are preferably of rather large size, and most of them desirably are square or of diamond shape, as indicated at 28. The apertures 27, at the ends of the waste grab preventer, preferably are triangular to complete a regular pattern of spaced-apart apertures occupying a laterally curved rectangular field. I prefer that the several apertures in each longitudinal row be staggered with respect to the apertures of the adjacent row or rows, as illustrated.

In that embodiment of my invention which is shown in Figs. 1 to 4 inclusive all of the inner surface of the waste grab preventer is smooth.

When the waste grab preventer is in cooperating relationship with the journal 11, the packing 22 and the bearing brass 17, as illustrated in Figs. 1, 2 and 3, all of the apertures 27 and 28 lie below the upper surfaces of those portions of packing 22 upon which the journal depends for direct lubrication, and such portions of the packing can only engage the cylindrical surface of the journal through such apertures. Flanges 24 stand ready to engage the lower lateral edges of the bearing brass 17 if the journal 11, when rotating in and with respect to the waste grab preventer, should tend to carry either of the longitudinal edges of the waste grab preventer between the journal and the bearing brass. I prefer that the flanges 24 shall be out of contact with bearing brass 17 when the waste grab preventer is initially installed—thus compensating in advance for expected wear of journal and bearing brass.

If any threads or chunks of the packing in contact with the cylindrical surface of the journal should adhere to the journal, when the journal starts from rest or at any other time when it is rotating, such threads or chunks of packing material can move only a very slight distance with the journal before they are scraped therefrom by the trailing margins or margin of the particular aperture 27 or 28 at and through which such threads or chunks of packing material are contacting the journal. Thus waste grabs are thwarted by a very simple and effective means which does not prevent the cylindrical surface of the journal from being effectively lubricated by the oil saturated packing. An additional but by no means inconsequential advantage afforded by the waste grab preventer of the present invention is attributable to the fact that when the journal comes to rest a substantial quantity of oil tends to collect, as a film bridging the narrow spaces between the smooth cylindrical surface of the journal and the opposed smooth inner surfaces of the waste grab preventer—such oil film affording the journal its initial lubrication when its rotation recommences.

I prefer to install the waste grab preventer as follows: With the journal box 10 jacked up and with the bearing brass 17 removed, the waste grab preventer, with its longitudinal edges extending downwardly, is slipped over the journal 11, to take a position between its collar 20 and its shoulder 21. Then the waste grab preventer is turned through 180° to its operating position depicted in the drawings.

The waste grab preventer of Figs. 5 to 8 inclusive differs from the waste grab preventer of the preceding figures only in that (a) it is provided with means arranged to interlock with the bearing brass to insure that the waste grab preventer shall not engage either the collar 20 or the shoulder 21 of the journal 11, and (b) it is provided with oil grooves in the inner surface of its perforate portion 26 to permit an increased quantity of oil to collect between the cylindrical surface of the journal 11 and the opposed inner surfaces of the waste grab preventer when the journal is at rest.

The portions of the waste grab preventer of Figs. 5 to 8 inclusive which interlock with the bearing brass 17 are the triangular lugs 29 which are turned upwardly from the flanges 24, and the integral extensions 30 of the waste grab preventer

which lie adjacent to but rise above the flanges 24. Triangular lugs 29 are adapted to engage the contiguous surfaces of the conventional stop lugs 31 of the bearing brass 17, to keep the right hand 5 end (Fig. 7) of the waste grab preventer from slipping into scraping engagement with the journal shoulder 21. The extensions 30, to which I have previously alluded, are adapted to engage the right hand ends (Fig. 7) of the stop lug extensions 10 32, to keep the left hand end of the waste grab preventer from slipping into scraping engagement with the journal collar 20.

The oil grooves in the perforate portion 26 of the waste grab preventer, which permit the 15 accumulation of a greater quantity of oil between the waste grab preventer and the cylindrical surface of the journal when the journal is at rest, are indicated at 33. Each of these grooves 33 preferably intersects and communicates with one 20 or more of the other grooves, as is most clearly illustrated in Fig. 6.

Under most practical conditions I find that the more simple form of waste grab preventer depicted in Figs. 1 to 4 both inclusive, will serve 25 just as satisfactorily as the more elaborate waste grab preventer depicted in Figs. 5 to 8 both inclusive. I find that the more simple form of waste grab preventer, when used in connection with the ordinary journal, tends to center itself between the journal collar 20 and the journal shoulder 21 in such a way that it does not objectionably scrape either of them when the journal is in motion. Moreover, I find that the more simple form of waste grab preventer will, when used 30 with the ordinary journal, develop a sufficient oil film between itself and the journal when the journal is at rest, notwithstanding that it lacks the oil collecting grooves 33 of Fig. 6.

In certain situations, however, the more elaborate form of waste grab preventer shown in Fig. 40 6 will justify the additional manufacturing expense which its added features entail.

Having thus illustrated and described my invention in connection with two practical embodiments thereof, what I claim as new and desire to 45

secure by Letters Patent of the United States is:

1. In combination a journal, a journal box, a journal-engaging box-supporting shoe and journal lubricating packing carried in the journal box; a waste grab preventer in the form of a partial sleeve of inherently springy metal embracing the cylindrical surface of the journal, said waste grab preventer extending more than 180° around the cylindrical surface of the journal and having its longitudinal edges lying adjacent the shoe, 10 apertures in said waste grab preventer through which the packing may contact the cylindrical surface of the journal, said waste grab preventer lying in the packing and said apertures lying below the upper surfaces of the packing, said 15 apertures being arranged in a plurality of longitudinal rows with some of said apertures staggered with respect to others.

2. A waste grab preventer consisting of a sheet of inherently springy metal having the shape of a partial sleeve adapted to embrace and extend more than 180° around the cylindrical surface of a packing lubricated shoe-supporting journal, a portion of said partial sleeve which is spaced from and lies intermediate its longitudinal edges being 20 provided with a multiplicity of apertures through which packing material may engage the cylindrical 25 surface of a journal which the waste grab preventer embraces.

3. A waste grab preventer consisting of a metal 30 sheet having the shape of a partial sleeve adapted to embrace and extend more than 180° around the cylindrical surface of a packing lubricated shoe-supporting journal, a portion of said partial sleeve intermediate its longitudinal edges being provided 35 with a multiplicity of apertures through which packing material may engage the cylindrical surface of a journal which the waste grab preventer embraces, the longitudinal edges of said waste grab preventer being normally resiliently urged to 40 a position such that the distance between them is less than the diameter of a journal to be engaged by such waste grab preventer.

WALTER M. GIBBS. 45
